CLAIM

The ornamental design for a brassiere, substantially as shown and described.

DESCRIPTION

FIG. 1 is a front perspective view of a brassiere, showing my new design;

FIG. 2 is a front elevational view thereof;

FIG. 3 is a rear elevational view thereof;

FIG. 4 is a front perspective view of a second embodiment of that shown in FIG. 1;

FIG. 5 is a front elevational view thereof; and

FIG. 6 is a rear elevational view thereof.
